(57) **CLAIM**

The ornamental design for an outlet box, as shown and described.

DESCRIPTION

FIG. 1 is an exploded top, front perspective view of an outlet box showing the new design in a disassembled state; FIG. 2 is a top plan view of the lid and box body of the outlet box;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof;

FIG. 8 is a top, front perspective view of the outlet box showing the new design with the lid attached to the box body in an open configuration;

FIG. 9 is a top perspective view of the outlet box showing the new design with the lid attached to the box body in a closed configuration; and,

FIG. 10 is a top perspective view of the outlet box with the lid attached to the box body, in the closed configuration, in an environment of use and assembled state.

The broken lines in the drawings illustrate environmental subject matter and portions of the article that forms no part of the claimed design.

1 Claim, 8 Drawing Sheets
